CLAIM

The ornamental design for a pressure washer, as shown and described.

DESCRIPTION

FIG. 1 is a front perspective view of the pressure washer; FIG. 2 is a bottom perspective view thereof; FIG. 3 is a front elevation view thereof; FIG. 4 is a rear elevation view thereof; FIG. 5 is a right elevation view thereof; FIG. 6 is a left elevation view thereof; FIG. 7 is a top plan view thereof; and, FIG. 8 is a bottom plan view thereof.

The broken lines in the figures illustrate portions of the pressure washer which form no part of the claimed design.
